REFRIGERATOR ICE DOOR CONSTRUCTION

Charles J. Gibson, Greenville, Mich., assignor to
 Gibson Refrigerator Company, Greenville,
 Mich., a corporation of Michigan

Application December 9, 1930, Serial No. 501,067

4 Claims. (Cl. 62—31)

This invention relates to refrigerators and more particularly to door constructions for the same.

An object of this invention is a refrigerator having an ice compartment and a plurality of food compartments separated therefrom and from one another by suitable partitions the refrigerator having a plurality of doors, one of which covers the ice compartment and one of the food compartments, the others of which cover one or more of the remaining food compartments, as desired. These doors generally are of the usual refrigerator type, that is to say, they are heavily insulated and are of comparatively expensive construction.

In such refrigerators, where there is provided a single door which covers both the ice compartment and a food compartment, opening the door to expose the food compartment will also expose the block of ice, thus permitting a substantial thermal loss from the ice compartment and a substantial decrease in the efficiency of the refrigerator.

Accordingly, there has been provided an inner door which is removable, when access to the ice compartment is desired, and which normally conceals the latter even when the outer door which covers the ice compartment and an adjacent food compartment is open. The inner door may be of comparatively inexpensive construction, that is to say, it may be made of a sheet of metal provided with suitable means for retaining it in place.

A further object, therefore, is a novel form of inner door for refrigerators of the class described above, the door being provided with a snap or spring fastening means by which it may be maintained in its place in front of the ice compartment.

Still other objects will readily occur to those skilled in the art upon reference to the following description and the accompanying drawing in which

Fig. 1 shows a refrigerator having two outer doors, one of which conceals the ice compartment and a food compartment and the other one of which covers a plurality of food compartments.

Fig. 2 is a front view of the ice compartment and a portion of the adjacent food compartments, the ice compartment being covered by the inner door forming part of the invention.

Fig. 3 is a side sectional view as if on the line 3—3 of Fig. 2.

Fig. 4 is a detail sectional view of a modification.

By reference to the drawing, it will be seen that the refrigerator 10 is provided with a pair of hinged doors 11 and 12 having the usual latches 13 and 14. Behind the doors 11 is an ice compartment 16 and a food compartment 18, separated from each other by a shelf 20 and a portion 22 of the refrigerator body. Behind the door 12 are a plurality of food compartments 26, separated from each other by the shelves or racks 28. The lining for the ice compartment 16 may be extended upwardly and offset as at 32 to provide a groove 34 between itself and an auxiliary strip 36 as disclosed, the bottom of the groove being in communication with the interior of the compartment 16 thru the minute apertures 37 in the bottom of the groove. Disposed within the groove 34 is a sheet metal door 38 whose upper edge 39 overlaps the lower edge 42 of the upper portion of the lining, and adjacent the upper edge 39 of the inner door 36, a more or less conventional snap fastener 44 is provided, there being a handle 46 of any suitable construction by which the upper edge of the door 38 may be drawn back so as to permit the door being removed from the groove and from the ice compartment.

In Fig. 4 the refrigerator is provided with one or more friction catches 50 secured to the upper edge of the ice compartment by a screw 52, the friction catch 50 having a shoulder at 54 behind which the door 36 may be disposed, the catch cooperating with the upper edge of the door in an obvious manner.

It will be seen that the inner door prevents thermal loss from the block of ice when the door 11 is opened, while at the same time, an economy in the construction of the refrigerator is effected by virtue of the door 11 covering both the ice compartment and a food compartment.

Further, the moisture which condenses on the inner side of the door 38 will collect on the shelf 20, draining thru the pipe 58, and will not collect on the inner surface of the door 11.

It will be observed therefore, that there has been provided a construction which prevents great thermal losses in refrigerators which have a door covering both the ice compartment and an adjacent food compartment, the inner door being of comparatively inexpensive construction as contrasted with the comparatively expensive construction of the outer door.

Further, it is contemplated to provide slides on the inside wall and the partition of the re-

frigerator so that the inner ice door is slideable, up and down, in front of and below the ice compartment, the construction being such that the ice door is not readily removable from the refrigerator.

Further, it is also contemplated to hingedly mount the ice door in front of the ice compartment, as desired, the hinge line being at the top or bottom (horizontal) or at the side (vertical).

Now, having described the invention and the preferred embodiment thereof, it is to be understood that the said invention is to be limited, not to the specific details herein set forth, but only by the scope of the claims which follow.

I claim:

1. In a refrigerator, an ice compartment and a food compartment separated from each other by a partition, a single outer door covering both of said compartments, and an inner door covering only the ice compartment, the inner door being made of comparatively inexpensive sheet metal, firmly although removably mounted in the ice compartment, the upper edge of the inner door being provided with a catch whereby it may be securely held in place in the ice compartment, and the lower edge of the inner door being supported in a grooved portion of the wall of the ice compartment.
2. In a refrigerator, an ice compartment and a food compartment separated from each other by a partition, a single outer door covering both of said compartments, and an inner door covering only the ice compartment, the inner door being made of comparatively inexpensive sheet metal, firmly although removably mounted in the ice compartment, the upper edge of the inner door being provided with a catch whereby

it may be securely held in place in the ice compartment, and the lower edge of the inner door being supported in a grooved portion of the wall of the ice compartment, the groove communicating with the interior of the ice compartment.

3. In a refrigerator, a plurality of compartments separated from one another by partitions and shelves, one of the compartments being an ice compartment and others being food compartments, an outer door which covers both the ice compartment and a food compartment, an inner door of comparatively inexpensive sheet metal, firmly but removably mounted in the ice compartment, the upper edge of the inner door being provided with a catch whereby it may be securely held in place in the ice compartment, and the lower edge of the inner door being supported in a grooved portion of the wall of the ice compartment.

4. In a refrigerator, a plurality of compartments separated from one another by partitions and shelves, one of the compartments being an ice compartment and others being food compartments, an outer door which covers both the ice compartment and one of the food compartments, an inner door of comparatively inexpensive sheet metal construction firmly although removably, mounted in the ice compartment, the upper edge of the inner door being provided with a catch whereby it may be securely held in place in the ice compartment, and the lower edge of the inner door being supported in a grooved portion of the wall of the ice compartment, the groove communicating with the interior of the ice compartment.
